FREDERIC M. CARD, OF BRIDGEPORT, CONNECTICUT, ASSIGNOR TO THE SINGER MANUFACTURING COMPANY, OF ELIZABETH, NEW JERSEY, A CORPORATION OF NEW JERSEY.

SEWING-MACHINE ATTACHMENT.

Application filed October 6, 1922. Serial No. 592,692.

To all whom it may concern:

- Be it known that I, FREDERIC M. CARD, a citizen of the United States, residing at Bridgeport, in the county of Fairfield and State of Connecticut, have invented certain new and useful Improvements in Sewing-Machine Attachments, of which the following is a specification, reference being had therein to the accompanying drawings.
- 5 This invention relates to improvements in work-severing mechanisms for sewing machines adapted to make the so-called open-work, spoke-stitch and hemstitch seams, whereby the cross-bars of the seams 10 may be severed to produce what is known as picot-edging. Work-severing mechanisms of this character are commonly termed picot-edging attachments.
- 15 Picot-edging attachments of prior construction may be divided into two classes, in one of which the lower or non-actuated blade is supported by a bracket sustained by the presser-bar of the sewing machine, as disclosed for instance in the United States 20 patent to C. M. Abercrombie, No. 1,098,003, May 26, 1914, and in the other of which the non-actuated blade is secured upon the cloth-plate or throat-plate of the machine, as disclosed for instance in the United States 25 patent to W. W. Hirk, No. 1,392,872, October 4, 1921. During the feeding of the work, the feed-dog is projected above the machine throat-plate, whereby the presser-bar is slightly lifted. Consequently, in the first 30 class of devices, it is essential to provide means for preventing the work from being fed under the lower blade which in the natural course would follow the movements of the presser-bar. A variety of devices 35 have been employed to this end, all of which complicate the construction and operation of the attachment. In constructions wherein the non-actuated blade is secured upon the machine throat-plate, a difficulty is immediately apparent in the turning of sharp 40 corners or curves in the work. Furthermore, when it is desired to change from picot-edging to straight hemstitching, it is necessary to stop the machine and detach the 45 parts to facilitate handling of the work and prevent severing thereof.
- 50 The present invention has for its object to provide a picot-edging attachment of simplified construction thoroughly efficient under various conditions of operation and 55 capable of being at will shifted into an ineffective position.
- To the attainment of the object of this invention, the cutting blades are pivotally supported upon a fulcrum-stud common to 60 both blades and sustained by a bracket adjustably secured upon a rigid support on the overhanging arm of the machine. The non-actuated blade is secured against incidental movement upon its pivotal support, in both 65 operative and inoperative positions, by means of a shifting- and securing-screw operating in a cam-slot provided in the blade-supporting bracket. In its operative 70 position the cutting end of the blade is preferably disposed in contact with the throat-plate and in its inoperative position, this 75 end of the blade is shifted about its pivotal support into a position above the tread-surface of the presser-foot. The movable 80 blade is linked to the usual piercer-actuating rock-shaft for actuation thereby, the two blades being yieldingly maintained in shearing relationship by a spring bearing 85 against the head of a screw threaded into the fulcrum-stud for the purpose of permitting ready removal of the blades for re-sharpening purposes.
- In the accompanying drawings, Fig. 1 is a 90 front end elevation of the head portion of an open-work stitching machine to which the present improved attachment has been applied, the left presser-foot being broken away to better illustrate the cutting blades. Fig. 2 is a rear side elevation of the machine 95 head. Fig. 3 is a view of the attachment from the side opposite to that shown in Fig. 1, with the right presser-foot broken away. Fig. 4 is a top plan view of a portion of the trimming knives illustrating their disposition with respect to the presser-feet and throat-plate. Fig. 5 is a detail sectional view of the blade supporting fulcrum stud substantially on the line $x-x$, of Fig. 3. Fig. 6 is a detail sectional view of the non-actuating blade shifting- and securing-screw, substantially on the line $y-y$, of 100 Fig. 3.

Referring to the drawings, the present improvement is shown as embodied in a 105 commercially well known sewing machine adapted to make an open-work seam. This machine includes a cloth-plate 1, a throat-

plate 2, a feed-dog 3, together with the usual overhanging arm terminating in the head 4. Journaled in the overhanging arm is the usual rotary actuating shaft 5 carrying the crank-pin 6 connected by means of the link 7 with the needle-bar 8 mounted for vertical reciprocatory movements in the head 4. The needle-bar carries two needles, as 9, (only one of which is shown) arranged in a line transverse to the direction of seam-formation and each adapted to be laterally vibrated by upwardly extending rods, as 10, (only one of which is shown). The rods 10 are adapted to be actuated in the usual manner in properly timed relation with respect to the movements of the feed-dog 3 to form an open-work seam. The needle-bar 8 also carries for endwise reciprocation the front piercer 11 having its usual function.

Also suitably journaled in the overhanging arm is the rock-shaft 12 adapted to be actuated from the shaft 5 and connected by means of an arm 13 with the piercer-bar 14 journaled for endwise movement in the head 4. The piercer-bar carries the usual piercer 15 for cooperation with the needles in the formation of an open-work seam. A spring-pressed presser-bar 16 is mounted for endwise movement in the head 4 and is provided at its lower end with left and right presser-feet 17 and 18. The presser-bar 16 is under the action of a coiled spring 19 interposed between an adjustable bushing 20 and a collar 21 secured upon the presser-bar by means of a set-screw 22. The collar 21 is provided with divergent lifter-lugs 23 and 24, the lug 23 being disposed in the path of movement of the hand lifter lever 25, acting upon said lug through the intermediary of the yielding wear-plate 26. The lug 24 projects into a slot 27 provided in a guide-bar 28 secured for vertical adjustment in suitable apertured lugs on the machine head by means of a screw 29. The interengagement of the lug 24 and the walls of the slot 27 prevents axial rotation of the presser-bar and at the same time said lug is subject to the action of the usual knee-controlled lever 30, of which the free end projects into the slot 27.

In the present construction the guide-bar 28 is lengthened to form a support for the cutting blades of the picot-edging attachment. To this end there is clamped upon the lower end of the bar 28, a collar 31 by means of a screw 32. Adjustably secured upon the collar 31 by means of screws as 33 is the laterally projecting shank 34 of a depending bracket 35. The lower end of this bracket 35 is formed with an aperture 36 entered by a fulcrum-stud 37 and affording a pivotal-support for the cutting blades 38 and 39. These blades are maintained in shearing relationship by means of

a coiled spring 40 interposed between the blade 39 and the head of a screw 41 threaded into the fulcrum-stud 37. The blade 38 is non-actuated in the severing action and in operative position its cutting end 42 is preferably disposed in contact with the throat-plate 2, whereby the work to be severed is compelled to ride up on the blade. This position of the cutting blade is rigidly maintained in the following manner. The rear end of the blade 38 is provided with an elongated slot 43 entered by a pin 44, projecting from the head 45 of a bolt 46, entering an elongated slot 47 provided in the bracket 35. The bolt 46 projects through the slot 47 and threaded upon its outer end is a securing nut 48 between which and the bracket 35 is interposed a washer 49. When the nut 48 is slightly loosened, the bolt 46 may be shifted by manipulation of the nut 48, in both of the slots 43 and 47. Inasmuch as the bracket 35 and consequently the slot 47 is rigid, the shifting of the bolt to its extreme forward position depresses the end 42 of the blade 38 into contact with the throat-plate, owing to the angular relationship of the slots 43 and 47. On the contrary, when the bolt 46 is shifted rearwardly, the cutting end 42 of the blade 38 is raised above the tread-surfaces of the presser-feet 17, 18, whereby the work is free to pass under said blade. The blade 38 is rigidly secured in both of these positions by tightening the nut 48, it being apparent that by reason of the construction described only a very slight turn of the nut 48 is essential to permit shifting of the bolt. Furthermore, this shifting may occur at any time at the will of the operator without interfering with the operation of the machine. The described construction of pivotal support for the blades 38, 39 permits ready detachment of the blades from the machine for resharpening or other purposes without interfering with the presser-foot or other operative parts.

The movable blade 39 is provided at its forward end with a cutting edge 50 for coaction with the cutting edge 42 and is connected at its rearward end by means of a pivot-screw 51 with a link 52, pivotally connected at its upper end to a collar 53 secured upon the piercer rock-shaft 12 by means of a screw 54. It is apparent that by means of this construction the cutting blade 39 will be actuated in unison with the piercer and that by reason of the disposition of the blades rearward of the needle-aperture 55 in the throat-plate and in alignment with a vertical plane through said aperture, the cross-bars of the open-work seam will be severed to produce what is known as picot edging. The end 42 of the non-actuated blade is disposed directly in the rear of the needle-aperture and as only the point of this blade rests upon the throat-plate, it is

clear that very sharp turns may be made without interfering with the picoting operation.

Having thus set forth the nature of the 5 invention, what I claim herein is—

1. The combination in a sewing machine including a throat-plate having a needle-aperture, an overhanging arm, a presser-foot, and stitch-forming and feeding mechanism for making an open-work seam, of 10 coacting blades having their cutting edges disposed rearwardly of the throat-plate needle-aperture and coacting in substantially a vertical plane through said needle-aperture, means upon said overhanging arm for rigidly supporting one of said blades, and means for actuating the other blade to sever the cross-bars of the open-work seam.

2. The combination in a sewing machine 20 including a throat-plate having a needle-aperture, an overhanging arm, a presser-foot, and stitch-forming and feeding mechanism for making an open-work seam, of coacting blades having their cutting edges disposed rearwardly of the throat-plate needle-aperture and coacting in substantially a vertical plane through said needle-aperture, means upon said overhanging arm for rigidly supporting one of said blades, 25 a pivotal support for the other blade, and means for actuating the pivotally supported blade to sever the cross-bars of the open-work seam.

3. The combination in a sewing machine 35 including a throat-plate having a needle-aperture, an overhanging arm, a presser-foot, and stitch-forming and feeding mechanism for making an open-work seam, of coacting blades having their cutting edges disposed rearwardly of the throat-plate needle-aperture and coacting in substantially a vertical plane through said needle-aperture, means upon said overhanging arm for rigidly supporting one of said blades in 40 both operative and inoperative positions, a pivotal support for the other blade, and means for actuating the pivotally supported blade to sever the cross-bars of the open-work seam.

50 4. The combination in a sewing machine including a throat-plate having a needle-aperture, an overhanging arm, a presser-foot, and stitch-forming and feeding mechanism for making an open-work seam, of coacting blades having their cutting edges disposed rearwardly of the throat-plate needle-aperture and coacting in substantially a vertical plane through said needle-aperture, means upon said overhanging arm for rigidly supporting one of said blades, 55 means for actuating the other blade to sever the cross-bars of the open-work seam, and means for at will rendering said movable blade ineffective.

65 5. In a sewing machine, the combination

with stitch-forming and feeding mechanism, and a throat-plate having a needle-aperture, of work-severing mechanism comprising a stationary blade having its cutting edge disposed in operative position 70 rearwardly of said needle-aperture and in substantial alinement therewith in the direction of feed, a movable blade coacting with said stationary blade, means for actuating said movable blade, a bracket rigidly sustaining said stationary blade in operative position, and means for at will shifting said stationary blade into and out of rigid operative position during the operation of the machine. 80

6. In a sewing machine, the combination with stitch-forming and feeding mechanism, and a throat-plate having a needle-aperture, of work-severing mechanism comprising a stationary blade having its cutting edge disposed in operative position rearwardly of said needle-aperture and in substantial alinement therewith in the direction of feed, a pivotal support for said stationary blade above the work side of said throat-plate, 85 means for securing the stationary blade against incidental movement upon its pivotal support during the operation of the machine, a movable blade disposed above the work side of the throat-plate for coaction with the stationary blade in the severing of the work, and means for actuating said movable blade. 90

7. In a sewing machine, the combination with stitch-forming and feeding mechanism, and a throat-plate having a needle-aperture, of work-severing mechanism comprising a stationary blade having its cutting edge disposed in operative position rearwardly of said needle-aperture and in substantial alinement therewith in the direction of feed, a pivotal support for said stationary blade, 100 means for securing the stationary blade against incidental movement upon its pivotal support during the operation of the machine and permitting the shifting at will of said stationary blade upon its pivotal support into operative and inoperative positions during the operation of the machine, a pivotally supported movable blade coacting 105 with said stationary blade in the severing operation, and means for actuating said movable blade. 110

8. In a sewing machine, the combination with stitch-forming and feeding mechanism, and a throat-plate having a needle-aperture, of work-severing mechanism comprising coacting blades having their cutting edges disposed in operative position rearwardly of said needle-aperture and in substantial alinement therewith in the direction of feed, a pivotal support common to both of said blades, means for rigidly securing one of said pivotally supported blades against incidental movement during the severing opera- 120 125 130

tion, and means for actuating the other of said blades upon its pivotal support.

9. In a sewing machine, the combination with stitch-forming and feeding mechanism, and a throat-plate having a needle-aperture, of work-severing mechanism comprising co-acting blades having their cutting edges disposed in operative position rearwardly of said needle-aperture and in substantial alinement therewith in the direction of feed, a pivotal support common to both of said blades, means for rigidly securing one of said pivotally supported blades against incidental movement during the severing operation, means for actuating the other of said blades upon its pivotal support, and means for yieldingly maintaining said blades in shearing relationship.
10. In a sewing machine, the combination with stitch-forming and feeding mechanism, and a throat-plate having a needle-aperture, of work-severing mechanism comprising co-acting blades having their cutting edges disposed in operative position rearwardly of said needle-aperture and in substantial alinement therewith in the direction of feed, sup-

porting and actuating means for said blades including a pivotal support common to both of said blades comprising a supporting bracket, a tubular fulcrum stud sustained by said bracket and entering fulcrum-apertures in said blades, a screw threaded into said fulcrum-stud, and yielding means for maintaining shearing relationship between said blades.

11. A picot-edging attachment for sewing machines comprising a supporting bracket provided with a cam-slot, a pair of cutting blades, a fulcrum-stud for said blades sustained by said bracket, means for maintaining said blades in shearing relationship, one of said blades being provided with a cam-slot adjacent to and inclined with respect to the supporting bracket cam-slot in the operative position of said blade, a securing bolt shiftably disposed in said cam-slots, and operative connections for actuating the other of said blades during the operation of the machine.

In testimony whereof I have signed my name to this specification.

FREDERIC M. CARD.
